UNITED STATES PATENT OFFICE

MAX E. LOBLEY, OF NEW YORK, N. Y., ASSIGNOR TO BROOKLYN COOPERAGE CO., OF BROOKLYN, NEW YORK.

METALLIC HOOP FOR BARRELS.

1,169,272.

Specification of Letters Patent. Patented Jan. 25, 1916.

Application filed October 19, 1914. Serial No. 867,285.

To all whom it may concern:

Be it known that I, MAX E. LOBLEY, a citizen of the United States, and a resident of the borough of Brooklyn, in the city of New York, county of Kings, and State of New York, have invented certain new and useful Improvements in Metallic Hoops for Barrels, of which the following is a specification.

10 My invention relates to hoops consisting of strips of sheet metal designed for use upon barrels, &c., for the purpose of securing the staves, &c., in position. Heretofore these strips of metal have been made with 15 "driving" beads and flanges of various shapes in cross section, all objectionable on account of the excessive width of metal required for their formation, and because they are apt to be broken or distorted when the 20 strip is bent to form the hoop. Obviously such drive beads or flanges require the use of a marginal area of metal over and above that of the broad flat bearing or body portion of the hoop contacting directly with 25 the staves, and this excess adds materially to the cost of manufacture, while affording only a "drive" which is easily broken down or impaired, not only in the process of bending of the metal to form the hoop as herein 30 tofore mentioned, but also because the driving operation tends to curl, compress or otherwise distort the drive bead or flange.

It is the main object of my invention to obviate these objectionable features, and to 35 afford a comparatively cheap, effective sheet metal hoop for the purpose designated, in which a minimum width of sheet metal strip is sufficient to afford a suitable "drive" edge entirely within the area of contact of the 40 hoop with the staves,—a "drive" edge that cannot be broken down or impaired by bending the strip into hoop form, nor by subsequent contact with the driving tool.

The invention comprises essentially a 45 hoop of the character designated having a driving edge consisting of a continuous, sinuous, undulatory series of corrugations, protuberant upon the outer face of the hoop only, and extending toward but not as far 50 as the longitudinal center of the hoop (less than one third the width of the hoop, by preference),—the inner terminal of each corrugation thus formed merging into the body of the hoop in the reverse curve the 55 length of which at the exterior medial line

or longitudinal outer crest of the wave or corrugation is of less length than the width of the corrugation, whereby the corrugations are stiffened and reinforced transversely of their length and better adapted 60 to resist the strain of the driving tool, so that the shape of the hoop is maintained in its integrity with a broad flat inner contacting surface for intimate engagement with the opposed outer surface of the barrel. 65 The driving edge thus formed readily yields and conforms without injury or distortion to the bending of the strip to form the hoop; the corrugations interlock where the ends of the strip overlap to form the hoop, 70 and thereby strengthen the hoop at its otherwise weakest portion by reinforcing the rivets; and the longitudinal elasticity imparted to the driving edge by the corrugations causes the hoop to adapt itself more 75 perfectly to the external surfaces of the staves, so that the hoop clings thereto in a most effective manner,—the broad, flat contacting surface of the hoop being supplemented by the teeth-like inner undulations 80 of the corrugations which impinge against the staves, embedding themselves therein to some extent, so as to act as retardants against retractile slip, looseness, or play.

In the accompanying drawings, Figure 1, 85 is a perspective view of the drive hoop; Fig. 2, an edge view of the overlapping ends thereof; Fig. 3, a front view of the parts shown in Fig. 2; Fig. 4, a cross section of the hoop and adjacent portions of a stave; 90 Fig. 5, a cross section of the drive hoop.

The hoop H , consists of a single strip of sheet metal h , having on one edge transverse corrugations h' , forming a continuous series of undulatory curves extending from 95 the inner side plane h^2 , of the strip outward laterally. That is to say the bottom or inner crest c , of each inner curve coincides with and is a continuation of the inner body plane h^2 , of the strip h , the protuberant portions or outer crests c' , of the curves extending beyond the outer plane surface h^3 , thereof, as shown more particularly in Figs. 4 and 5. By reference to these figures it will also be seen that the corrugations h' , extend inward less than one third the width of the hoop (preferably, as in the drawings about one fourth the width thereof as in actual practice) and that the inner 100 end of each corrugation terminates and 105 110

merges into the flat body h , of the hoop in the form of a relatively short reversed curve c^2 , the length of which on the longitudinal center of the corrugation and in alignment 5 with its outer crest c' , is less than the mean width of the corrugation so that the latter is stiffened and reinforced both longitudinally and transversely to withstand the driving strain, while at the same time more 10 than three-fourths of the interior surface of the body of the hoop is left free and unobstructed for actual, direct, and intimate contact with the bilge of the barrel to which the hoop is applied.

15 To form the hoop H , the strip h , of suitable length is bent with the flat plane surface h^2 , inward, the ends of the strip overlapping and interlocking as shown in Figs. 1 and 2, and being riveted together through 20 the flat body portions in the usual manner. It has been found that this interlocking of the corrugations h' , where the ends of the strip overlap, greatly increases the strength of the joint,—so much so that the strip will 25 yield and tear laterally under test strain while the rivets hold intact, and hence it is possible in this construction of hoop to use smaller rivets than heretofore without weakening the hoop,—a result of practical 30 value and importance in the manufacture of hoops in large quantities. For a like reason the economy effected in the width of material used to form this drive hoop is of vast importance where such hoops are 35 turned out by the million, as for sugar barrels and the like, where the saving of a small fraction of an inch of the width of the metal strip h , means a corresponding saving of a cent or two per barrel. And by my construction 40 I am not only enabled to use a sheet metal “drive” hoop made from a minimum width of material but also, by reason of the special form and strengthening and stiffening effect of the relatively short corrugations, I am enabled to use thinner sheet metal 45 than heretofore, since my “corrugated edge drive” bears the brunt of the tightening operation without danger of disintegration or collapse. In fact, for that matter, the strain 50 during the tightening operation being transverse to the corrugations the latter are able to stand and preserve their shape and integrity under any pressure to which they may be thus subjected, owing largely to the 55 transverse stiffening effected by the relatively short reversed curvature c^2 , of the metal at their ends where they merge into the body of the hoop, so that the flat body portion thereof is fully reinforced and protected 60 against any strain to which it could possibly be subjected under ordinary conditions of use. As a consequence I am enabled to use a lighter weight or grade of sheet metal in the formation of the hoops 65 than has heretofore been possible, and thus

effect a double economy in manufacture in that I use a thinner strip of less width, with the result that I attain a hoop of maximum strength with a minimum of material and cost, and all this while affording a hoop 70 superior in simplicity and effectiveness of structure. And the combined saving in weight involved in the use of narrower strips of lighter material may be considered as equivalent to at least three cents per barrel of the “slack barrel hoop” type to which latter my improvements are particularly 75 adapted, although not necessarily limited thereto.

It is thus obvious that the making of the 80 “drive” entirely within the maximum width of the hoop is a most valuable and distinctive feature of my invention, since it not only simplifies and cheapens the structure but also affords a snugly fitting hoop which 85 clings tenaciously to the staves,—the broad flat surface of relatively thin material adapting itself perfectly to the contour of the staves, while the stiffened yet elastic “drive” edge tends to impinge therein,— 90 the crests c , of the inner curves of the corrugations acting as teeth which bite more or less into the outer surfaces of the staves, owing to the customary flare of the hoop 95 and the usual stress of the driving operation,—sufficiently so at least to prevent any slip or retractile movement of the hoop under ordinary conditions of use while not interfering with the further drive of the 100 hoop if necessary to compensate for shrinkage.

Used as a slack barrel hoop my device effectually holds the staves in position and prevents their slipping, overlapping &c., 105 in the manner heretofore well known in the art relating to slack barrel hoops, and which it is one of the objects of my invention to obviate. Furthermore my corrugated edge drive renders the hoop more “springy” and elastic and better adapted to conform to 110 the slight irregularities of shape or structure apt to occur in the manufacture of “slack” barrels. The “drive edge” is also better adapted than the bead drive to slide over skids in the handling of the loaded barrels, since it is less likely to catch thereon.

It is to be noted that my corrugations are not only short as related to the width of the hoop but also that the side edges thereof are 120 parallel, not convergent. That is to say the corrugations are of the same uniform width transversely from top to bottom, even where they blend into the flat body of the hoop. This is clearly shown in the drawings, the 125 only exception to this parallelism being the reversed curvatures c^2 , shown more particularly in Figs. 4 and 5, where the outer crests c' , of the corrugations h' , merge into the flat main body portion h , of the metallic strip. Comparing Fig. 4, with Fig. 2, it 130

will thus be seen that my drive edge is composed of corrugations in which the metal has been made to assume reverse curve lines only, there being a total absence of longitudinal convergence of the side edges of the corrugations, and of sharp angular transition from one part of form to another. In other words the displacement or flow of the metal effected in the formation of my metallic hoop is exclusively on one side of the general plane of the strip, and the drive edge is attained wholly by the formation of reversed curves or wave lines which from their very nature stiffen and reinforce the constituent corrugations longitudinally as well as transversely, thus creating perfect, ideal annular impact-receiving means of great and uniform strength, blending with and into the broad flat body of the strip in such manner as to impart and distribute the strain of the driving tool evenly to the parts and side of the hoop which contact directly and positively with the opposed surface of the barrel to which the hoop is applied. As a result of this specific structure I am enabled to use a comparatively light weight or grade of sheet metal in the formation of a hoop of prescribed strength and tenacity, thereby effecting economy in cost, transportation, manipulation, &c.

What I claim as my invention and desire to secure by Letters Patent is,

1. A hoop of the character designated, comprising a strip of sheet metal formed with a driving edge consisting of a continuous series of sinuous, undulatory corrugations protuberant upon the outer face only of the hoop so as to leave the inner surface of the inner crests of the corrugations in alinement with the flat inner face of the hoop, said corrugations being of substantially equal width with parallel edges extending transversely toward the

longitudinal center of the hoop for a distance not exceeding one-third the width of the hoop, the overlapping ends of the strip being united to complete the hoop.

2. A hoop of the character designated, comprising a strip of sheet metal formed with a driving edge consisting of a continuous series of sinuous, undulatory corrugations protuberant upon the outer face only of the hoop so as to leave the inner face of the inner crests of the corrugations in alinement with the flat inner face of the hoop, said corrugations being of substantially equal width with parallel edges extending transversely toward the longitudinal center of the hoop for a distance not exceeding one third of the width of the hoop and merging into the body of the latter at their inner ends in the form of reversed curves, the overlapping ends of the strip being united to complete the hoop.

3. A hoop of the character designated, comprising a strip of sheet metal formed with a driving edge consisting of a continuous series of sinuous, undulatory corrugations protuberant upon the outer face only of the hoop so as to leave the inner face of the inner crests of the corrugations in alinement with the flat inner face of the hoop, said corrugations being of substantially equal width with parallel edges extending transversely toward the longitudinal center of the hoop for a distance not exceeding one third of the width of the hoop and merging into the body of the latter at their inner ends in the form of reversed curves of less length than the corrugation width, the overlapping ends of the strip being united to complete the hoop.

MAX E. LOBLEY.
